HYDROSTATIC BAILER

Clifford E. Van Stone and Arthur E. Johnson,
Taft, Calif.

Application October 31, 1938, Serial No. 237,852

3 Claims. (Cl. 166—19)

This invention is a compensating hydrostatic bailer, that is, it is a bailer for use in wells where there is a stand of water above the well muck which is to be cleaned; and the bailer is provided with an elongating or upper barrel part valved at its top to normally close when this barrel part is pulled upwardly as to the bailer bottom or bucket section while this is at rest in or on the bed of well stand or muck.

Such pulling of the valved, upper part of the bailer unbalances the static pressure of the liquid in the bailer relative to that without with the result that the higher outside pressure tends to cause an inflow of the well liquid and muck into the bailer.

The bucket section of the bailer is inlet-valved and it will be seen that by repeatedly reciprocating the barrel part on the stationary bucket structure the bailer may be quickly filled to a load capacity for greater than is possible in simple, one part bailers.

A further object is to provide a simple, substantial, practical and efficacious jar function bailer to expedite the drive of the bailer bottom into stiff or thick muck, or to aid in jarring loose some other obstacle or "fish" in the well, or to aid in forcing it into the bucket.

Also, it is an object of the invention to provide a suction, cross-area piston of maximum size in a given size of bailer shell.

Additionally it is an object to provide a bailer bucket header or stem having telescopic relation with the barrel part and provided with a piston having packed working or sliding relation in the barrel, and especially to locate mutually engaging shoulders on the bucket stem and the barrel at a position below the packing device so as to substantially eliminate sanding up of the barrel by forcing all sand out.

A further object is to provide a simple, reliable and interiorly arranged combined trap valve for muck inlet and a side wall, port covering valve device for side dump of the elevated, that is, drawn bucket at the top of the well.

The invention consists in certain improvements advancing this art as set forth in the ensuing disclosure and having, with the above, additional objects and advantages as hereinafter developed, and whose construction, combinations and details of means, and the manner of operation will be made manifest in the description of the here-with illustrative embodiment; it being understood that modifications, variations and adaptations may be resorted to within the scope, spirit

and principle of the invention as it is more directly claimed hereinbelow.

Figure 1 is an axial, elevational section of the bailer with the barrel and the buckets parts in the position assumed when either lowering into or pulling the bailer from the well hole.

Figure 2 is a cross- or trans-axis section of the closed, side dumping valve and bucket wall.

Figure 3 is an axial section of the detached jar-swivel.

The bailer assembly includes at its upper end a rope socket or bail joint 2 the lower end of which is chambered to receive a suitable, downwardly closing valve ball or equivalent member 3 past which liquid or gas may rise to vents ports 4 in 15 the valve cage.

The ball 3 seats on a renewable ring 5 clamped in the cage end of joint 2 as by a threaded-in connection 6 whose lower end is threaded into the upper end of a cylindrical barrel 8. The lower 20 end of the barrel is bushed by a bucket pulling nut 9 presenting a top abutment face 10 just below equalizing ports 11 in the well of the barrel.

A feature of this invention is the provision of a bucket stem 12 of tubular form more or less 25 snugly fitting in the bushing nut 9 and having screwed on its upper end a mandrel or head 13 slidably fitting the bore of the barrel 8 and having a bore 14 of about the same dimension as that of the hollow stem 12.

In order that advantage may be taken of the full diameter of the bore of the working barrel 8 it will be seen that the head 13 has a reduced upper part 15 about which is a stack of downwardly facing, V-section packing rings 16, Fig. 3, 35 bearing outwardly directly against the bore face of the barrel 8 so that this maximum diameter of the bore is availed of for suctional function when the barrel is relatively shifted upward as to the stem head 13. The packing 16 is clamped 40 down by a mandrel nut 17.

Opposed to the abutment face 10 on the bush nut 9 the stem head 13 is provided with a cooperative strike end 18; the faces 10 and 18 being engaged when the bailer is being lowered or 45 drawn.

The mandrel nut 17 constitutes also a substantial anvil to receive the pounding of the lower end of connector 6 which has the function of hammering down on the stem anvil part 17 as 50 may be desired occasionally in lowering the bailer into the well and muck.

The lower end of the stem 12 is threaded into the upper end of a bailer connector 19 welded or otherwise secured to the top of a bucket 20 of 55

about equal outside dimension to the outside diameter of the barrel for capacity advantage in being lowered into a well casing or liner.

A feature of the invention resides in an improved form of bottom inlet valve and side unloading means for bailers of this general type. The lower end of the bucket 20 is provided with a durable bucket bottom 21 into which snugly screws a serrated, wear shoe 22 of tubular form 10 for up flow of liquid, gas and muck as the bottom 21 sets down in the well; the shoe having upwardly opening check valve 23 suitably pivoted at 24, and formed on or fixed to the upper end of the shoe 22 is an upright wall part forming a laterally shiftable closure 25 lying operatively close to the bore face of the bottom 21 for the purpose of normally closing a contiguous side discharge port 26 in the wall of the bottom 21.

The closure 25 is in cross-section a portion of 20 an annulus and is suitably wider than the annular port 26 to amply cover it, and the outer face of the closure 25 may be provided with packing 27 to seal marginally about the port 26.

To unload the bailer at the head of the well, the 25 shoe 22 is relatively turned a quarter revolution or so in the bottom 21 to uncover the side port 26, and is reversed the same degree to close it. To protect the screw threads of the shoe 22 any suitable packing 28 may be set between the end 30 edge of the bottom 21 and the top thread of the shoe; to keep fine sand from the threads.

When the bailer bucket is landed on the bottom of the well hole the upper barrel 8 may be reciprocated as to the standing piston-forming 35 head 13 on the bucket stem 12 to facilitate filling

the bucket, and during such action the well liquid may flow in and out of the ports 11 to wash out any sand that may collect between the lift shoulders at nut 9.

What is claimed is:

1. A bailer, of the class described, having an upper valved barrel section provided with a thin walled bushing in its lower end presenting a narrow edged, annular hammer in the bore of the barrel and the barrel having breather ports 10 above and near said edge, and a lower bucket unit having a thin walled stem telescoping in the bushing and provided with a thin walled piston matching said hammer edge and operative to close said ports when opposite thereto and the 15 piston having a packing running on the barrel bore surface; said piston being valveless and having a clear bore of about equal diameter to the bore of the stem so that the bucket, the barrel and the stem have an unobstructed chamber of 20 as uniform diameter as practical for carrying capacity.

2. The bailer of claim 1, and the piston being threaded onto the stem and having a reduced outer upper end portion for the packing, and an 25 annular nut on the upper end of the piston to form an anvil for impingement by an upper part of the barrel.

3. The bailer of claim 1, and the piston having a reduced upper, outer portion for the packing 30 and having a nut to compress the packing and forming a renewable anvil for impingement by a part of the barrel.

CLIFFORD E. VAN STONE.

ARTHUR E. JOHNSON.
